WADE H. REICHARD, OF ROCHESTER, NEW YORK, ASSIGNOR TO GENERAL RAILWAY SIGNAL COMPANY, OF ROCHESTER, NEW YORK

AUTOMATIC TRAIN-SPEED-CONTROL SYSTEM FOR RAILROADS

Application filed May 21, 1925. Serial No. 31,840.

This invention relates to automatic train control systems for railroads, and more particularly to that type of system now commonly known as a continuous control system, which employs alternating current in the track rails and controls inductively electro-responsive means on the car.

In one type of the so called continuous control systems, a three-position relay is employed on the locomotive, and this relay is caused to assume any one of its three different positions, in accordance with traffic conditions, by the control of the flow of alternating current in two circuits including the track rails. One of the currents in the track rails, conveniently termed the track phase or loop circuit current, flows in the track rails in opposite directions at any given instant, like the ordinary track circuit current. The other current, conveniently called the line phase or simplex circuit current, flows in the two track rails in multiple and is displaced in phase with respect to the track phase current.

A system such as just described provides for three distinctive influences or controls, available for enforcing three different speed limits, for example, or for other automatic control as may be considered necessary. In applying automatic train control to railroads, however, it is found desirable, in order to provide automatic control of train movements efficiently and with the least delay, to have more than three fixed speed limits. In short, it is found expedient to be able to set up at any desired point along the railroad, under a given traffic condition, any particular speed limit desired.

In order to provide such desirable flexibility and to make available a relatively large number of speed limits from which to select, it is proposed in accordance with the present invention to utilize the time-distance interval principle in connection with continuous inductive control systems, and to provide for the automatic application of the brakes at any selected point along the track if a train exceeds any predetermined speed limit at that point as may be selected or found expedient, under clear, caution, or danger traffic conditions, as may be required. This flexi-

bility of speed limits is employed to advantage, particularly in providing a tapering speed control to enforce obedience to caution signals.

A train traveling in a danger or occupied block should not, for reasons already understood by those familiar with the art, exceed some predetermined low or minimum speed limit, such as 15 or 20 miles per hour. Since such minimum speed limit is to be continuously imposed, and may be the same for all blocks, it is proposed in accordance with this invention to employ a speed-responsive device driven from the car wheels, in conjunction with associated controlling mechanism, to provide such minimum speed limit, and arranged to apply the brakes if that speed limit is exceeded at any point in said danger block.

A further feature or object of this invention relates to the provision of means for automatically applying the brakes at each caution signal, or corresponding control point, unless the engineer takes appropriate action, conveniently termed acknowledgment, in recognition of the caution indication and as a manifestation of his vigilance. Also, it is proposed to require such acknowledgment upon the approach to a stop signal, such acknowledgment being possible only if the train has been brought below the minimum speed limit, and the point of such acknowledgment being preferably braking distance for that minimum speed in the rear of the stop signal.

Other characteristic features, functions, objects and advantages of the invention will be in part apparent and in part more fully explained as the description progresses.

One specific embodiment of the invention has been selected; and in describing this particular embodiment reference will be made to the accompanying drawings, in which:

Fig. 1 shows the track equipment and a portion of the car equipment, together with some braking curves and speed limit lines illustrated to facilitate explanation; and

Fig. 2 shows car apparatus and circuits, with the exception of the receiving coils and amplifiers illustrated in Fig. 1.

The selected embodiment of the invention has been illustrated in the accompanying drawings in a simplified and diagrammatic manner, employing established and well known conventions, the manner of illustration being adopted more for the purpose of facilitating understanding of the nature of the invention, than with the idea of showing the particular construction and arrangement of parts and circuits that might be used in practice to the best advantage.

Trackway equipment

Referring to Fig. 1, the track rails 1 are divided by insulating joints 2 into blocks in the usual way and in conformity with recognized block signal practice. Only one complete block C and the adjacent ends of two other blocks B and D have been shown. The parts and circuits associated with each of the several blocks are assumed to be the same, and for convenience corresponding parts will be given the same reference characters with distinctive exponents.

Extending along the trackway is a transmission line TL, supplied with alternating current, preferably of a commercial frequency, such as 60 cycles, from a suitable source indicated as a generator 3. The use of alternating current track circuits is assumed for the particular embodiment illustrated; and the secondary of a track transformer 4 is connected across the track rails 1 at the exit end of each block, said connections including a limiting inductive reactance or impedance 5. Associated with each block is a track relay T; and as shown this track relay is of the two element or polyphase type shown in accordance with established convention. The track phase winding of the track relay T is connected across the track rails at the entering end of each block in the usual way; but the local phase winding 6 of each track relay, instead of being directly connected to the alternating current supply, in this instance is connected in a circuit including the secondary of a transformer 7 and a front contact 8 of a check or safety relay 9, which is preferably a single phase relay of suitable construction.

Across the track rails 1 at the entrance end of each block is connected a non-inductive balancing resistance 10; at an intermediate point near the exit end of the block is a similar resistance 11; and at the exit end of the block is another resistance 12. The intermediate point in the block, at which the balancing resistance 11 is located, is conveniently referred to as the point B; and this point B is braking distance from the exit end of the block for the low or minimum speed selected, assumed to be about 20 miles per hour. Alternating current is impressed across the middle points of these resistances 10, 11 and 12 of different relative instantaneous polarities under different traffic conditions, under the control of the

track relay of the next block in advance. As shown, a transformer 13 is used for supplying current to the line phase or simplex circuits of each block.

Under clear traffic conditions, alternating current of the normal instantaneous polarity is supplied across the middle points of the balancing resistances 10 and 12 by a circuit which may be readily traced as follows:—commencing at one terminal of the secondary of the transformer 13¹, limiting resistance 14¹, front-contact 15¹ of the track relay T¹, wire 16, balancing resistance 12, along the track rails, other balancing resistance 10, wire 17, check relay 9, wires 18 and 19, front contact 20¹ of track relay T¹, and wire 21¹ to the opposite terminal of said secondary.

Under caution traffic conditions, that is, with the block next in advance occupied, alternating current of the reverse instantaneous polarity is applied across the resistance 10 and 11 and through the line wire including wires or loops L adjacent to one of the track rails. For example, referring to the block C and assuming the block D next in advance to be occupied, the circuit for the track phase or simplex current may be traced as follows:—commencing at one terminal of transformer 13¹, resistance 14¹, contact finger 15¹ of track relay T¹, and its back contact, line wire 22 including in series the three track loops L, L¹ and L², wire 18, check relay 9, wire 17, balancing resistance 10, through the track rails 1 in multiple, balancing resistance 11, wire 23, back contact and contact finger 20¹ of track relay T¹, and wire 21¹ to the opposite terminal of said secondary.

Thus, under clear traffic conditions the line phase current of normal polarity is supplied throughout the length of the block between the balancing resistances 10 and 12; whereas, under caution conditions, this current is of reverse polarity and is between resistances 10 and 11 only, said line phase current also flowing through the track loops L. In a danger or occupied block, the flow of line phase current is not changed from normal, unless the block next in advance should also be occupied; but in such occupied block the track phase current is cut off from a following train by the shunting action of the wheels and axles of the leading train in the block.

The line phase or simplex circuit current flowing in the track rails in multiple is preferably made resistive with a minimum amount of inductive reactance, so that the current is nearly in phase with the transmission line voltage; and the track phase or loop circuit current, flowing down one rail and back the other at any given instant, is on the other hand made reactive so that the current therein lags with respect to the transmission line voltage. Such phase displacement of the current in the track phase and line phase may, however, be obtained in other ways.

5 Trackway block signals of a suitable type are preferably used with the train control system; and a three-position semaphore signal Z is shown at the entrance to each block, no attempt being made to illustrate its control circuits, which may be of any suitable form now commonly used in automatic block signalling.

The track loop

10 The track loop L is a wire or cable suitably supported close to one of the track rails and insulated from it. One preferred form of track loop comprises a wire or cable with a heavy insulating body of suitable material 15 protected from mechanical injury and weather, which is fastened by suitable clips against the web of the rail. The wire of the track loop may be inclosed in a metal conduit bolted against the web of the rail underneath the head. As shown, each track loop consists of 20 one run or turn adjacent to the track rail, but a plurality of turns are used to advantage in most instances, the other side of each run or turn being at some distance from the rail 25 so that its magnetic field will not materially influence the receiving coils on the locomotive. The various loops at different points along the track are different in length corresponding to the particular speed limit it is 30 desired to enforce. These track loops are conveniently referred to as speed loops; and as shown, there are three speed loops L, L¹ and L² for the block C.

Car equipment

35 The influence receiving equipment for the car, shown diagrammatically in Fig. 1, comprises two receiving coils P and P¹, with or without laminated iron cores, which are carried over opposite track rails at the front end and in the rear of the engine and tender. These coils are resonated by condensers in the usual way and are connected to the input circuits of suitable amplifiers A and A¹, the output 40 circuits of which are connected to the field windings 26 and 27 of a two element or polyphase alternating current relay MR of the vane or rotor type. This main car relay MR is provided with contact fingers in the usual 45 way and is biased to a neutral or de-energized position. One finger is shown in Fig. 1; and this finger is moved to one extreme position with both field windings 26 and 27 energized with currents having one phase relation, is 50 shifted to the other extreme position when both field windings are energized but with the current of one field winding reversed, and to the de-energized position when either 55 or both of the field windings are de-energized.

60 In a clear block, the track phase and line phase currents supplied to the rails have the normal phase relation, and the contact fingers of the main car relay MR assume one extreme position, shown in full lines, conven-

iently called the normal position. In that portion of a caution block in the rear of the point B, both track phase and line phase currents are flowing, but these currents have an opposite phase relation; and the contact fingers of the main car relay MR assume the other extreme or reverse position. In a caution block between the point B and the end of the block, the line phase current is cut off, de-energizing the winding 27 of the relay MR 75 and causing its contact fingers to assume the neutral or de-energized position. In a danger or occupied block, the track phase current is shunted by the wheels and axles of the forward train, thereby de-energizing the field 80 winding 26 of the relay MR on the following train, and causing its contact fingers to assume the neutral or de-energized position. This operation, thus briefly outlined, is characteristic of the typical 3-position continuous inductive control system, employing track phase and line phase, and a point B; and being familiar to those skilled in the art, needs no detailed explanation.

Fig. 2 shows diagrammatically the parts of the car-carried apparatus, together with their circuit connections. This car apparatus includes a suitable speed responsive device SD, driven from the car wheels; and this device SD acts to open contacts at all speeds 90 above some selected minimum speed, such as 18 or 20 miles per hour. This speed responsive device SD is shown as of the conventional centrifugal type mounted on a shaft 28, connected in some suitable manner (not shown) 100 to the car wheels or axles; and at speeds above the minimum speed, this centrifuge moves a contact disc 29 out of engagement with co-operating insulated contact springs 30.

In addition to the main car relay MR, already described, the car apparatus includes four other relays preferably of the direct current tractive type, which are suitably constructed in a manner forming no part of the present invention so as to open and close their 105 contacts in different time relations with respect to the opening and closure of their energizing circuits. The relay S is a slow release relay, and once energized, does not open its contacts upon interruption of its energizing circuit until after the lapse of a short time interval, assumed for convenience to be about one-half second. The relay TD is also a slow release relay, constructed to open its contacts upon de-energization thereof 110 after a longer time interval, assumed to be one and one-half seconds. The relay TU is a slow pick-up relay, and when energized requires a certain interval of time, assumed to be about one-half second, to close its contacts 115 after closure of its energizing circuit. The relay Q is quick acting, closing and opening its contacts quickly upon energization and de-energization thereof.

The car apparatus also includes a manually 120

operable device, conveniently termed an acknowledging contactor, which is located in the cab within reach of the engineer, and is intended to be operated by the engineer every time a caution or danger signal is passed or corresponding control takes effect, such manipulation on the part of the engineer constituting an act of acknowledgment in recognition of the unfavorable change in traffic conditions. In the simplified form shown, this acknowledging contactor AC comprises a plunger 31 supported in suitable guides as 32, which is urged to the upper extreme position by a spring 33 between the guide 32 and a collar 34 on said plunger. A pivoted lever or handle 35 has one end engaging the collar 34, so that when said lever is raised the plunger 31 is moved downward. The plunger 31 carries two insulated contact discs or members 36 and 37 which bridge cooperating contacts (indicated conventionally as arrows) when the plunger is in its lowermost position. One end of a lever 38, pivoted at an intermediate point, rests upon the upper end of the plunger 31, and the other end of this lever is pressed upward by a spring 39, bearing against a suitable stop. The spring 33 is stronger than the spring 39. The rocking movement of the lever 38, in response to the expansion of the spring 39 upon downward movement of the plunger 31, is retarded by a suitable timing device, which in the form shown comprises a rod 40 pivotally connected to the lever 38 at one end and to a piston 41 with a flexible packing at the other end. The piston 41 works in a cylinder 42 having a restricted orifice 43 in the upper end. It will be evident that the upward movement of the piston rod 40 is gradual, depending upon the slow escape of the confined air through the orifice 43, but the downward movement is quick, air passing readily upward past the piston 41. When the lever 38 has been rocked by its spring 39 to an extreme position, its end opens a pair of contacts 44.

It will be observed that this acknowledging contactor AC is essentially a manually operable circuit controller by which two circuits may be closed at the contact members 36 and 37, and that, if the contactor is held in its active contacting position for more than a predetermined interval of time, other contacts 44 are automatically opened. Obviously, other combinations and arrangements of devices may be employed to attain these functions; and it should be understood that the particular construction of acknowledging contactor diagrammatically shown is merely illustrative.

It is assumed that the usual air-brake equipment is automatically controlled to produce a brake application by means of an application valve AV, in turn controlled by an electro-pneumatic valve EPV. Various forms of automatic brake control devices may

be employed; but in the particular arrangement shown, the brake control device or application valve is of the type shown, for example, in the patent to W. V. Turner, No. 1,309,787, July 15, 1919. This type of application valve AV comprises a piston 45, with a restricted opening 46 therein, the left hand side of which is exposed to main reservoir pressure, and the right hand of which is acted upon by a spring 47. The enclosed chamber 48 on the right hand of the piston 45 is connected by a pipe 49 to an enclosed chamber 50 in the lower part of the electro-pneumatic valve EPV, this chamber 50 also communicating with a timing reservoir 51. The electro-pneumatic valve EPV is of any suitable slow acting type of construction; and when its coils are energized, it holds a valve 52 seated, and when de-energized, permits this valve to be opened by a spring or air pressure and exhaust the chamber 50 to atmosphere through an exhaust port 53. The slow action may be obtained by use of copper rings around the core or other expedients.

Also connected to the chamber 48 on the right hand side of the piston 45, by a pipe 54, is an expansible pressure responsive device 55, which in the form shown comprises two ends connected by metallic bellows, one end being fixed and the other end movable. The movable end is connected to a rod 56 which carries insulated contact members 57 and 58 arranged to engage contacts (shown as arrows) when the bellows of the device 55 collapse upon release of pressure therefrom, due to the resiliency of the bellows themselves. In short, contact members 57 and 58 are in the open position when a predetermined pressure exists in the chamber 48 and are closed when this pressure drops to a certain value.

The car apparatus also includes suitable cab signalling or indicating means, which may take the form of lamps of different colors, or lamps illuminating backgrounds having different letters or insignia thereon, or any other suitable form. In the simplified form shown, it is assumed that three lamps will at times be lighted to illuminate suitable letters such as G, Y and R, corresponding to different train controlling conditions.

Operation

The operation is most conveniently described and explained in connection with various assumed traffic conditions. Assume that the train is traveling in a clear block, the contact fingers of relay MR being in the normal position shown, and the other parts and circuits being also in the condition shown in Fig. 2. For simplicity, various circuits have been shown as extending from one point, designated B, indicating a connection to one terminal of a car battery or other suitable source

to another point C, indicating a connection to the outer terminal of the battery.

Under normal conditions, the electro-pneumatic valve EPV is energized by a circuit which may be traced as follows:—commencing at B, contact finger 60 of the relay MR normal, wire 61, contacts 44 of the acknowledging contactor, wire 62, winding of valve EPV to C.

With the contact finger 63 of the relay MR in the normal position, the cab signal lamp or indicator G is lighted by a circuit, which will be obvious. With the contact finger 64 of the relay MR in the normal position, the slow pick-up relay TU is energized by a circuit as follows:—commencing at B, contact finger 64 normal, wires 65 and 66, relay TU to C.

Assuming the parts in the normal position shown and the train traveling at some speed above the minimum speed, so that the speed contacts 29—30 are open, suppose that the train passes from a clear block into a caution block, the contact fingers of the relay MR shifting from the normal position to the reverse position. If the engineer is vigilant in the observance of the wayside signals, he will know when his train is about to enter a caution block; and as a manifestation that he is alert and recognizes the existence of unfavorable traffic conditions ahead, he is required to operate the acknowledging contactor AC. He must do this before the train enters the caution block and the relay MR assumes its reverse position, thereby de-energizing the relay TU, which opens its contacts quickly upon its de-energization. Assuming that the engineer acknowledges properly, upon depression of the plunger 31 to move the contact member 37 into engagement with its contacts, an energizing circuit for the relay Q is established, as follows:—commencing at B, contact finger 67 and its front contact of relay TU, wires 68 and 69, contacts 37, wires 70 and 71, relay Q, and wire 72 to C. The relay Q at once closes its front contacts; and when the relay MR is reversed, and the relay TU is de-energized, a circuit for maintaining the valve EPV energized is established as follows:—commencing at B, finger 67 and the back contact of relay TU, wire 73, finger 74 of relay Q and its front contact, wires 75 and 76, contacts 44 of acknowledging contactor, wire 62, valve EPV to C. The valve EPV is made slow acting, as previously explained, so that it will not open and apply the brakes during the short interval of time intervening between the opening of its normal energizing circuit at the finger 60 of the relay MR, and its normal contact and the closure of the auxiliary energizing circuit just traced. After the relay Q has been energized in this manner, it is maintained energized by a stick circuit so long as the contact finger 63 of the

relay MR remains in the reverse position, this stick circuit being traced as follows:—commencing at B, finger 63 reversed, wire 78, finger 79 of relay Q and its front contact, wires 80, 81 and 71, relay Q, wire 72 to C.

If the engineer fails to acknowledge the caution signal properly, and therefore fails to pick up the relay Q, then the valve EPV is de-energized long enough to open, whereupon pressure is exhausted from the chamber 48 through the exhaust port 53 much faster than it can be supplied through the small opening 46, in said piston, thereby causing said piston to be shifted to the right in opposition to the spring 47 and produces an automatic brake application. When the pressure drops in the chamber 48, the contacts 57 and 58 close. If the engineer then operates his acknowledging contactor AC, the relay Q is energized by a circuit as follows:—commencing at B, contacts 58, wires 77 and 69, contacts 37 of acknowledging contactor, wires 70 and 71, relay Q and wire 72 to C. The car relay MR being in the reverse position, the relay TU is de-energized; and with this relay Q energized, the valve EPV is energized throughout the circuit hereinbefore traced, through the back contact of finger 67 of relay TU and front contact of finger 74 of relay Q.

Although such re-energization of the valve EPV closes the exhaust from the chamber 48, nevertheless the piston 45 does not at once return to the normal position shown and permit the release of the brakes, because the pressure must equalize on opposite sides of the piston before this can happen; and on account of the timing reservoir 51, it takes some time for the pressure, flowing through the small hole 46 in the piston 45, to build up to normal. Consequently, irrespective of restoration of the valve EPV, the brakes cannot be released for a time; and this time interval is selected to be long enough to assure stopping of the train. It is preferred to permit release of the brakes after a time in this way, rather than by operation of a reset device, accessible only from the ground because of the difficulty in locating such a reset device so that it can not be improperly manipulated, and also can be easily manipulated under all conditions encountered in practice, such as in tunnels, on trestles and the like. It will be observed that the release of the brakes does not take place automatically, but only after the engineer has made a positive act by operating his acknowledging contactor.

Speed limits in a caution block

As the rear receiver P¹ passes over a track loop L in a caution block, the car relay MR is operated from the reverse position to the normal position. This is because each turn of this speed loop L carries the same line

phase current as is flowing in both rails and produces upon the receiver P^1 the same resultant effect as if the line phase current were again reversed, that is, were of the normal instantaneous polarity. In other words, with the train moving in a caution block the instantaneous direction of flow of current in the receiver P is actually reversed each time this receiver is under a loop L ; this because the current in the loop wire is substantially again as large as the current flowing in the lower rail l , so that loop current not only neutralizes the effect of the rail current but actually predominates thereover to a sufficient degree to operate the relay MR to a normal position. The speed loops may have any desired number of turns to accomplish this end, it being, of course, evident that only one side of each turn should be close to the track rail.

At the time the train approaches a speed loop in a caution block, assuming that no automatic brake application has previously occurred due to failure of the engineer to acknowledge or due to excessive speed, the relay Q is energized by its stick circuit; the relay TD is maintained energized by a circuit through the finger 64 of relay MR , wire 82, relay TD and wire 83 to C ; the relay TU is de-energized; and the valve EPV is maintained energized by its auxiliary holding circuit hereinbefore traced. When the contact fingers of the car relay MR shift from the reverse to the normal position as the train comes over a speed loop, the relay Q is de-energized on account of the opening of its stick circuit at the finger 63; and while the fingers of the relay MR are in the normal position, the valve EPV is maintained energized by its normal circuit through the finger 60 of relay MR and its normal contact. Obviously the green lamp G will be energized so long as the relay MR is in its normal position upon passage of the train by a loop L . During the movement of the main relay MR from its normal position to its reverse position upon leaving such loop the relay Q will remain in its energized position long enough to allow its stick circuit to be completed through contacts 63 and 79, this by reason of the fact that its pick-up circuit through the armatures 84 and 87, to be described below, is not immediately broken upon such change in the relay MR and also because a certain amount of time is required for the relay Q to drop. The relay TD is de-energized, but does not open its front contacts until after one and one-half seconds; and the relay TU is energized, but does not close its front contacts until after a half second.

Assume that the speed of the train is low enough so that the rear receiver P^1 does not leave the speed loop until after the lapse of one-half second, giving the relay TU time to close its front contacts, the front contacts of

the relay TD not yet having opened. Under these conditions a pick-up circuit for the relay Q is established as follows:—commencing at B , finger 84 of the relay TD and its front contact, wires 85 and 86, finger 87 of relay TU and its front contact, wires 88, 81 and 71, relay Q , and wire 72 to C . Then, when the contact fingers of the relay MR return to the reverse position after the train passes off of the speed loop, the stick circuit for the relay Q is established, and upon de-energization of the relay TU , the auxiliary holding circuit for the valve EPV is established, and no brake application occurs. In other words, the relay Q is de-energized at every loop L and is again picked up if the speed of the train by such loop is low enough to allow sufficient time for the relay TU to pick up and complete the pick-up circuit for relay Q just traced. In this connection, it should be remembered that during the passage of the vehicle by a loop L the normal circuit for the device EPV is closed. The operation is similar to that occurring when the engineer manually acknowledges, but this operation occurs automatically, provided the slow pick-up relay TU has time to close its front contacts during the interval of time intervening between the reversing of the contact fingers of the car relay MR .

If the speed of the train is such that the relay TU does not close its front contacts before the fingers of the car relay MR return to their reverse position, then the valve EPV is de-energized, its normal energizing circuit being broken at the finger 60 of the relay MR , and its auxiliary energizing circuit being broken at the finger 74 of the relay Q , which has not been re-energized. Consequently, an automatic brake application occurs, and the brakes cannot be released until after operation of the acknowledging contactor and the lapse of a predetermined time, the same as previously explained.

From this explanation it will be evident that any desired speed limit may be enforced at any desired point along the track in a caution block by installing a speed loop at that point having a length corresponding to the speed limit desired. For instance, assuming one-half second timing for the car apparatus, a speed loop of 22 feet would result in automatically applying the brakes upon a passing train at any speed above about 30 miles per hour.

Fig. 1 shows diagrammatically for the purpose of explanation speed-distance braking distance curves of performance of trains under automatic brake applications, and a speed-distance brake application curve. The brake application curve 90 shows the speeds at the various points in the block at which, if the valve EPV opens and initiates an automatic brake application, such brake application will cause the train to follow the braking

distance curve 91 and be brought to a stop before reaching the end of the block. Assuming the use of three speed loops L , L^1 and L^2 spaced approximately as illustrated, the length of the first loop L should be such as to enforce a speed limit not greater than the speed indicated by the point on the application curve 90 corresponding to the location of the next speed loop L^1 , so that a train cannot pass the first loop L at any speed so high that a brake application occurring in the next speed loop L^1 will fail to stop the train short of the end of the block, the possibility of the train accelerating between speed loops being taken into account if desired. The same explanation applies to the length of the second loop L^1 . The speed limit for the last loop L^2 in the block is preferably made the same as the minimum speed limit of, say, 20 miles per hour. The selection of the number of loops in a caution block, and the speed limits enforced by each loop is susceptible of variation and adaptation to fit different conditions; and it should be understood that the specific example just given does not have to be followed out.

Change from caution to clear

If, while the train is traveling in a caution block, this block changes to clear, due to the removal of the danger condition in the block next in advance, the car relay MR instantly responds, changing the cab signal indications and restoring the car apparatus to the normal condition. At the same time all of the speed restrictions are instantly wiped out, since the line phase current is then conducted over the line wire 19 instead of over the line wire 22 through the trackway speed loops. Hence, the engineer is immediately advised of a change in traffic conditions ahead and is permitted to accelerate.

Entering a danger block

As the train passes the point B near the exit end of the caution block, the car relay MR is de-energized, and the engineer is required to acknowledge the stop signal. This point B will of course in practice be sufficiently conspicuous to the engineer to enable him to make the acknowledgment at the proper point, and if the signal ahead is not visible to the engineer from such point B practice would dictate the use of a repeater signal. It may be explained here that the point B is preferably located at least braking distance for the minimum speed from the exit end of the block, so that a brake application occurring at this point due to failure of the engineer to acknowledge, will result in stopping the train short of the end of the block.

When the car approaches the point B, the relay Q is energized by its stick circuit, the relay TU is de-energized, and the relay TD ener-

gized. If a train has been properly governed and is traveling at some speed below the minimum speed, so that the speed contacts 29-30 are closed, and if the engineer in obedience to the stop signal indication operates his acknowledging contactor AC before passing the point B, the relay S is energized by a circuit as follows:— commencing at B, finger 60 of relay MR reversed, wires 92 and 93, contacts 36 of acknowledging contactor, wire 94, finger 95 of relay Q and its front contact, wires 96 and 97, speed contacts 29-30, wire 98, relay S and wire 99 to C. When the fingers of the relay MR assume the de-energized position, the relay TU is energized; and with the relay S energized, a pick-up circuit for the relay Q is established through the finger 100 of relay S and its front contact, wires 101 and 86 and finger 87 and the front contact of relay TU. With the relays Q and S energized, the valve EPV is maintained energized by a circuit from B, finger 102 of relay and its front contact, wire 103, finger 104 of relay Q and its front contact, wires 105 and 76, contacts 44 and wire 62 through EPV to C. The relay S is maintained energized, so long as the speed is below the minimum speed limit and the car relay MR is de-energized, by a circuit commencing at B, finger 106 of relay MR and its neutral or back contact, wire 107, finger 108 of relay S and its front contact, wires 109 and 97, speed contacts 29-30, wire 98, relay S and wire 99 to C. With the relay S energized, the cab indicator R is lighted by a circuit which can be readily traced.

A train may continue to travel through the danger or occupied block at any speed below the minimum speed. If this minimum speed limit is exceeded, the relay S is de-energized, and the brakes are automatically applied. The relay S is a stick relay, its stick contact comprising contact 108. If this stick relay S is de-energized by reason of excessive speed resulting in opening contacts 29-30, it can only be picked up by acknowledgement and then only if the contact 57 associated with the application valve AV is closed and the speed is low enough to close contacts 29-30. This pick-up circuit may be traced as follows:— beginning at the terminal B of a suitable battery, contact 57 of the brake application valve AV, wires 92^a and 93, contact 36 of the device AC, wire 94, contact 95 of the relay Q (this relay being energized if the acknowledging device AC is operated and the device AV, is in the brake applying condition), wires 96 and 97, contacts 29-30, wire 98, winding of the relay S, wire 99, to the common return wire C to the other side of said battery.

At points where track switches are encountered, it is desirable to provide suitable protection against the possibility of trains running on the main track being thrown into

a siding at an excessive speed, causing a derailment. This is usually accomplished by providing suitable contacts, commonly known as switch box contacts, which are operated in accordance with the position of the track switch and are connected in some suitable control circuit, for instance the track circuit. In the present embodiment, it is assumed that the switch box contacts are connected in the track circuit in such a manner that if the switch is open, that is, set for a turn out move, the track circuit is broken and the block in which the switch is located becomes a danger block by reason of the de-energization of the track relay at its entrance end. This siding protection does, however not by itself, constitute a part of the present invention.

If the track switch is set to its open position before an approaching train has entered the block in which the switch is located or the first block in the rear thereof, danger and caution control conditions will be set up in these two blocks respectively, and the train speed will be restricted in the manner described above in connection with the usual control in danger and caution blocks. If, however, the track switch is thrown to its open position while an approaching train is located in the first block to the rear of the block in which the switch is located, the engineer is given no warning as to the change of control conditions, and hence he can not acknowledge in time to prevent the de-energization of the electro-pneumatic valve, and an automatic brake application will result, bringing the train to a stop as described above in connection with passing a caution signal unacknowledged. Similarly, if the track switch is thrown to its open or turn out position while a train is traveling in the block in which such switch is located, the engineer receives no warning and hence does not acknowledge, and the brakes are automatically applied until the train is brought to a stop as hereinbefore described.

From the above it is evident that the system of the present invention affords protection to an approaching train against the improper setting of a track switch, the extent of restriction imposed depending upon the location of the approaching train when the switch is improperly thrown. In this connection it should be observed that the same protection as that just described is afforded when a track rail is broken, when a train ahead backs into a block in the rear or when, for any other reason, the track circuit in a given block is interrupted. As already hereinbefore explained in a general way, the track phase and line phase currents are preferably displaced in time phase, that is, the track phase current preferably lags in time phase behind the line phase current. By reason of this fact any current flowing in the track

rails, which flows so as to inductively affect both of the reservoirs P and P¹ will not by itself produce a torque in the relay MR, this because they are not displaced in time phase. In other words, the relay MR is of such construction that two currents displaced in phase are necessary to actuate the same.

In applying a continuous inductive system of train control to railways, certain points are encountered at which it is impossible to maintain the flow of control current because of interruptions in the continuity of the track rails at switch frogs, cross-overs, junctions between successive blocks and the like. In the systems of the invention, a brake application resulting from a momentary de-energization of the main relay MR is prevented by the slow acting feature of the electro-pneumatic valve EPV, described above. The electro-pneumatic valve is preferably arranged to act so slowly that the longest un-energized section of trackway ordinarily encountered may be traversed without the de-energization of the electro-pneumatic valve, provided the train is moving above a given speed.

As this invention has been described in a rather specific manner and in connection with several specific means and devices for carrying out its operation, it should be clearly understood that certain changes in such devices and apparatus could be made without departing from the scope of the invention. It should be further understood that certain well known expedients could be combined with the system of the present invention without departing from its scope as defined by the appended claims.

What it is desired to secure by Letters Patent is:—

1. In an automatic train control system of the type in which control influences corresponding to traffic conditions are continuously transmitted from the trackway to a moving vehicle, car-carried apparatus comprising means for causing a brake application upon the transmission of influences corresponding to unfavorable traffic conditions, manually actuatable means for suppressing said brake application if actuated before and released after the transmission of said unfavorable influences and trackway means comprising loops at spaced points having portions thereof located adjacent to the track rails and being energized under unfavorable traffic conditions to transmit influences for limiting the speed of the vehicle to a predetermined value.

2. In an automatic train control system of the type in which influences corresponding to traffic conditions are continuously transmitted from the trackway to a moving vehicle, car-carried apparatus for causing a brake application in response to influences corresponding to unfavorable traffic conditions,

- manually operable means for preventing said brake application if actuated before said influences are received, and means for limiting the vehicle speed under unfavorable traffic 5 conditions to a predetermined finite value comprising track loops, energized under unfavorable traffic conditions, and arranged to transmit influences to a moving vehicle for a predetermined distance of its travel at spaced points.
3. In an automatic train control system of the type in which control influences corresponding to traffic conditions are continuously transmitted to a moving vehicle from the trackway, in combination with the usual track rails divided into blocks, spaced trackway means in each block extending for different distances each setting up a restrictive speed limit depending on the distance it extends if the next block in advance is occupied, and car-carried speed responsive means for limiting the vehicle speed to a fixed value when the vehicle is traveling in an occupied block.
4. In an automatic train control system, means for transmitting influences corresponding to traffic conditions continuously from the trackway to a moving vehicle, means including spaced trackway influence transmitting means of limited extent for limiting the vehicle speed to a value depending on such extent under caution traffic conditions, and a car-carried speed responsive device for limiting the vehicle speed to a safe value under danger traffic conditions.
5. In an automatic train control system of the type in which control influences corresponding to traffic conditions are continuously transmitted inductively from the track rails to a moving vehicle, means for applying the vehicle brakes upon the reception of influences corresponding to caution or danger traffic conditions, manually actuatable means for preventing such brake application if actuated before a change to unfavorable traffic conditions, spaced trackway means of predetermined extent for cooperating with timed car-carried means to operate said brake applying means if a given speed is exceeded under caution traffic conditions, and a car-carried speed responsive device for causing the operation of said brake applying means if a given speed is exceeded under danger traffic conditions.
6. In an automatic train control system of the continuous inductive type in which control influences are transmitted inductively from the trackway by current flowing in the track rails; in combination, a car-carried apparatus including a normally inactive brake control device which has a tendency to assume its active condition, and means for preventing said brake control device from becoming active to apply the brakes if intermittent control influences are received inductively from current flowing in the trackway, said last mentioned means being inactive if the time of duration of said intermittent control influences be less than a predetermined value; and of trackway means for intermittently transmitting control influences by current flowing in trackway circuits including the track rails to said car-carried apparatus in accordance with traffic conditions ahead as the vehicle carrying such car-carried apparatus moves along the trackway.
7. A train control system of the continuous inductive type in which control influences are transmitted from the trackway to the vehicle in response to alternating current flowing in the track rails comprising, a normally inactive brake control device on a vehicle tending to assume its active condition to apply the brakes, means for preventing said brake control device becoming active if control influences are continuously transmitted from the trackway to the vehicle, and means for preventing said brake control device becoming active if the vehicle speed is not excessive and if control influences are transmitted intermittently to the moving vehicle in response to current flowing in trackway circuits including the track rails.
8. A train control system of the continuous inductive type in which control influences are transmitted from the trackway to the vehicle in response to alternating current of a particular frequency flowing in trackway circuits including the track rails ahead of such vehicle, a normally inactive brake control device on a vehicle tending to assume its active condition to apply the brakes, means for preventing said brake control device becoming active if such alternating current influences are continuously transmitted from the trackway, and means for preventing said brake control device becoming active if the vehicle speed is not excessive and if alternating current influences of said frequency are transmitted intermittently to the vehicle as it moves along the trackway in response to alternating current flowing in such trackway circuits including such track rails.
9. In an automatic train control system of the type in which influences corresponding to traffic conditions are transmitted from the trackway to a moving vehicle, a normally energized electro-pneumatic valve for exhausting a fluid pressure reservoir when de-energized and thereby initiating a brake application, means for de-energizing said valve in response to the transmission of influences corresponding to unfavorable traffic conditions, and manually actuatable means for maintaining said valve energized if actuated while influences corresponding to favorable traffic conditions are being transmitted, said fluid pressure reservoir having a volume such that said brake application can not be released for a predetermined time sufficient to bring the

train to a stop with the brakes applied after said valve has been re-energized.

10. In an automatic train control system, in combination with trackway means for continuously transmitting influences corresponding to traffic conditions to a moving vehicle, car-carried apparatus comprising a normally energized brake control device adapted to initiate a brake application when de-energized, 5 a three-position main relay controlled in accordance with said influences to assume positions corresponding to clear, caution and danger traffic conditions and adapted to maintain said brake control device energized when 10 in its clear position, an auxiliary energizing circuit for said brake control device, a relay for closing said auxiliary circuit when energized, a pick-up circuit for said relay which is closed if a manually actuatable circuit controller is actuated while said main relay is in 15 its clear position, a stick circuit for said relay which is closed only when said main relay is in its caution position, spaced trackway means for causing said main relay to assume its clear 20 position under caution traffic conditions for a predetermined distance of vehicle travel, and means for closing an auxiliary circuit for maintaining said relay energized while said main relay assumes its clear position provided 25 more than a predetermined time interval is consumed by the train in traveling said predetermined distance, whereby said brake control device is maintained energized and a 30 brake application is avoided provided a given speed is not exceeded under caution traffic 35 conditions.

11. In an automatic train control system, in combination with trackway means for continuously transmitting influences corresponding to traffic conditions to a moving vehicle, car-carried apparatus comprising a normally energized brake control device adapted to initiate a brake application when de-energized, car-carried means controlled in 40 accordance with said influences and adapted to maintain said brake control device energized under favorable traffic conditions, an auxiliary device for maintaining said brake control device energized when operated, manually actuatable means for operating said auxiliary device if actuated before the reception of influences corresponding to unfavorable traffic conditions, and spaced trackway means, active under unfavorable traffic 45 conditions to release said auxiliary device and to de-energize said brake control device if a predetermined speed is exceeded.

12. In an automatic train control system of the type in which control influences corresponding to traffic conditions are continuously transmitted inductively from the trackway to a moving vehicle, in combination with the usual track rails divided into blocks, car-carried apparatus comprising a normally energized 55 brake control device adapted to in-

itiate a brake application when de-energized, car-carried means controlled in accordance with said influences and adapted to maintain said brake control device energized under favorable traffic conditions, an auxiliary device for maintaining said brake control device energized when operated, manually actuatable means for operating said auxiliary device if actuated before the reception of influences corresponding to unfavorable traffic 70 conditions, spaced trackway devices of limited extent, active, when the next block in advance is occupied, to release said auxiliary device and so to de-energize said brake control device if a predetermined speed is exceeded, and a vehicle carried speed responsive device active when the vehicle is traveling in an occupied block to de-energize said brake control device if a more restrictive predetermined speed is exceeded. 75

13. In an automatic train control system of the type in which control influences corresponding to traffic conditions are transmitted from the trackway to a moving vehicle, spaced trackway means of limited extent, active under certain unfavorable traffic conditions to cooperate with timed car-carried devices to produce a brake application if a given speed is exceeded, and a car-carried speed responsive device for causing a brake 90 application if a given speed is exceeded under more unfavorable traffic conditions. 95

14. In an automatic train control system of the type in which control influences corresponding to traffic conditions are transmitted from the trackway to a moving vehicle continuously through the medium of current flowing in the track rails, in combination with the usual track rails divided into blocks, spaced trackway means in each block for cooperating with car-carried apparatus to set up increasingly restrictive speed limits if the next block in advance is occupied, and a car-carried speed responsive device for limiting the vehicle speed to a fixed value when the vehicle is traveling in an occupied block. 100

15. In an automatic train control system of the continuous inductive type, car-carried apparatus comprising a normally energized brake applying device, adapted when de-energized to initiate a brake application, means for de-energizing said brake applying device under unfavorable traffic conditions, a normally de-energized stick relay, acting when energized to maintain said brake applying device energized under unfavorable traffic conditions, a manually operable contactor for energizing said stick relay, and a timed contact associated with said contactor for de-energizing said brake applying device if said contactor is maintained closed for more than a predetermined time interval. 110

16. In an automatic train control system of the type in which control influences corresponding to traffic conditions are continu- 115 120 125 130

ously transmitted from the trackway to a moving vehicle, car-carried apparatus comprising a normally energized brake applying device acting when de-energized to initiate a brake application, means for opening a normally closed energizing circuit for said brake applying device upon the reception of influences corresponding to unfavorable traffic conditions, a normally de-energized stick relay acting when energized to close an auxiliary energizing circuit for said brake applying device, a manually operable contactor for energizing said stick relay if operated before the reception of influences corresponding to unfavorable traffic conditions, and means associated with said contactor for de-energizing said brake applying device if said contactor is maintained closed for more than a predetermined time interval.

20 In testimony whereof I affix my signature.

WADE H. REICHARD.
